(57) **CLAIM**

The ornamental design for a package carrier handle, as shown and described.

DESCRIPTION

FIG. 1 is a perspective view of a package carrier handle; FIG. 2 is a right side view of the invention, the left side view being a mirror image;

FIG. 3 is a top plan view of the invention;

FIG. 4 is a front elevation view of the invention;

FIG. 5 is a bottom plan view of the invention;

FIG. 6 is a perspective view of the invention in use carrying a package; and,

FIG. 7 is a further perspective view of the invention in use carrying a package.

The broken lines in FIGS. 6 and 7 are for purposes of illustration only and form no part of the claimed design.
